(57) CLAIM

The ornamental design for a cylinder operated by fluid pressure, as shown.

DESCRIPTION

FIG. 1 is a top, front and left side perspective view of a cylinder operated by fluid pressure showing my new design; FIG. 2 is a front view thereof; FIG. 3 is a rear view thereof; FIG. 4 is a top plan view thereof; FIG. 5 is a bottom plan view thereof; FIG. 6 is a right side view thereof; and, FIG. 7 is a left side view thereof.

Portions of the cylinder operated by fluid pressure are shown in broken lines for illustrative purposes only and form no part of the claimed design.
